CLAIM

The ornamental design for a case for earphone, as shown and described.

DESCRIPTION

FIG. 1 is a front, right and top perspective view of a case for earphone, showing my design.

FIG. 2 is a rear, left and bottom perspective view of the case for earphone in FIG. 1.

FIG. 3 is a front elevation view of the case for earphone in FIG. 1.

FIG. 4 is a rear elevation view of the case for earphone in FIG. 1.

FIG. 5 is a left side elevation view of the case for earphone in FIG. 1.

FIG. 6 is a right side elevation view of the case for earphone in FIG. 1.

FIG. 7 is a top plan view of the case for earphone in FIG. 1.

FIG. 8 is a bottom plan view of the case for earphone in FIG. 1; and,

FIG. 9 is a front elevation view of the case for earphone with a lid in a closed state.

The broken lines in the drawings depict portions of the case for earphone that form no part of the claimed design.
